ELECTROLYTIC PREPARATION OF 3-AMINO-2-OXAZOLIDONES

Gabriel Gever, Oxford, N. Y., assignor, by mesne assignments, to The Norwich Pharmacal Company, Norwich, N. Y., a corporation of New York

No Drawing. Original application February 28, 1952, Serial No. 274,067, now Patent No. 2,652,402, dated September 15, 1953. Divided and this application July 29, 1953, Serial No. 371,173

1 Claim. (Cl. 204—74)

This invention relates to a new series of chemical compounds and the preparation thereof. The series consists of a number of closely related 3-amino-2-oxazolidones. They are described by the general formula:

wherein

R is a member of the group consisting of hydrogen, lower alkyl and hydroxy (lower) alkyl

R₁ is a member of the group consisting of hydrogen, lower alkyl and hydroxy (lower) alkyl

R₂ is a member of the group consisting of hydrogen, lower alkyl and hydroxy (lower) alkyl, and

R₃ is a member of the group consisting of hydrogen, lower alkyl and hydroxy (lower) alkyl

The new compounds of the series are particularly useful as intermediates for the preparation of members of a series of N-(5-nitro-2-furyl)alkylidene-3-amino-2-oxazolidones, notably, N-(5-nitro-2-furfurylidene)-3-amino-2-oxazolidone, which I have invented and which form the subject of my co-pending application, Serial No. 274,066, filed February 28, 1952, now Patent No. 2,742,462. This application is a division of my co-pending application Serial No. 274,067, filed February 28, 1952, now Patent No. 2,652,402.

The various members of the new series of 3-amino-2-oxazolidones can be prepared by the electrolytic reduction of the corresponding 3-nitro-2-oxazolidone derivative. In this method, sulfuric acid is employed as the catholyte, lead as the anode, a mercury pool as the cathode, and a current density of 0.204 amp./cm.² is used for one hour at a temperature of 5° to 10° C. This reduction produces the desired 3-amino-2-oxazolidone derivative from the corresponding 3-nitro-2-oxazolidone.

In order that my invention may be entirely available to those skilled in the art, the preparation of members of the new series of compounds, including the new compound 3-amino-4,4-dimethyl-2-oxazolidone, by the method which I have invented is described briefly:

EXAMPLE I

3-amino-2-oxazolidone

2

3-nitro-2-oxazolidone is reduced electrolytically, using 160 cc. of 10% sulfuric acid as the catholyte, a lead anode, a mercury pool cathode and a current density of 0.204 amp./cm.² for one hour at a temperature of 5–10° C. At the end of this time the aqueous solution is separated from the mercury.

EXAMPLE II

3-amino-4,4-dimethyl-2-oxazolidone

4,4-dimethyl-3-nitro-2-oxazolidone (3.96 g.) is reduced electrolytically under the conditions given in Example I. After the aqueous solution is separated from the mercury, it is neutralized with barium hydroxide, the barium sulfate removed by filtration and the filtrate evaporated in vacuo to remove the water. The residue is taken up in a small amount of absolute alcohol, the excess barium hydroxide filtered off, and the filtrate distilled. After the removal of the alcohol, the 3-amino-4,4-dimethyl-2-oxazolidone distills at 130–135° C./10 mm.

What I claim is:

The method of preparing a 3-amino-2-oxazolidone represented by the formula:

wherein

R represents a member of the group consisting of hydrogen, lower alkyl and hydroxy (lower) alkyl

R₁ represents a member of the group consisting of hydrogen, lower alkyl and hydroxy (lower) alkyl

R₂ represents a member of the group consisting of hydrogen, lower alkyl and hydroxy (lower) alkyl

R₃ represents a member of the group consisting of hydrogen, lower alkyl and hydroxy (lower) alkyl

which comprises electrolytically reducing a 3-nitro-2-oxazolidone represented by the formula:

wherein R, R₁, R₂ and R₃ have the significance above given, by suspending the 3-nitro-2-oxazolidone in a catholyte of dilute sulfuric acid connected with a lead anode and a mercury pool cathode, and using a current of a density of about 0.204 amp./cm.² at a temperature of about 5–10° C.
